CLAIM

The ornamental design for a solar powered folding wall light, as shown and described.

DESCRIPTION

FIG. 1 is a front perspective view of a solar powered folding wall light showing my new design;

FIG. 2 is a back perspective view thereof;

FIG. 3 is a bottom perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof; and,

FIG. 10 is a right side view showing the solar powered folding wall light in an installation status.
